UNITED STATES PATENT OFFICE

EDWARD B. HOWE, OF OLYMPIA FIELDS, ILLINOIS

TYPE-PAGE FRAME

Application filed March 2, 1928. Serial No. 258,502.

This invention relates to improvements in page frames, or means for holding in place the type and printing elements which form the page so that the page or type form can be readily handled or stored without danger of becoming disassembled. The device is more especially intended for use in connection with regular forms and shapes of type bodies, such as the advertising pages of magazines and the like, which vary only slightly in dimensions.

One of the objects of this invention is to provide a holder or frame which can be readily applied to the type form, so that a considerable saving in time can be accomplished over the method of tying up the forms with string, which has been the usual practice.

A further object is to provide such a device which is durable in construction and which can be used repeatedly.

A still further object is to provide a page frame which is low in cost so that it can be used in quantities for storage purposes.

Another object is to provide such a device of such construction that it may be made mainly of stamped, sheet metal parts.

A further object is to provide resilient clamping members so that the type is held under a uniform pressure which is just sufficient to prevent the type from loosening and dropping out, and which will compensate for any slight differences or changes in the dimensions of the type form.

A still further object is to provide a holder having continuous sides so that the type can be straightened up or justified in case it has become slightly disarranged.

A further object is to provide a page frame which is securely locked when in the holding position, but which can be readily loosened so that type can be easily removed and corrections made.

Other objects, advantages and capabilities will later more fully appear.

My invention further resides in the combination, construction and arrangement of parts illustrated in the accompanying drawings, and while I have shown therein a preferred embodiment I wish it understood that the same is susceptible of modification and

change without departing from the spirit of my invention.

In the accompanying drawings:

Fig. 1 is a perspective view of a page frame embodying my invention, shown in locking position on a type page;

Fig. 2 is a longitudinal section of Fig. 1;

Fig. 3 is a section taken on the line 3—3 of Fig. 2;

Fig. 4 is a transverse section taken on the line 4—4 of Fig. 2;

Fig. 5 is a perspective view of the holder, with a part shown in the locked position;

Fig. 6 shows the holder unlocked;

Fig. 7 is a section of the end of the same with the locking elements partly down.

The frame is preferably of sheet metal construction, and consists of the open ended frame member 1, to which is hinged the bail or end frame member 2. The frame member 1 is formed into a U-shape with a flange 3 extending outwardly around the upper edge thereof for strengthening the sides, and also for facilitating the handling. At the transverse portion 4 of the closed end of the frame, the metal is bent up to form the resilient abutment strip 5 on the inside of the frame. The sides of the frame member 1 extend the whole length of the form so that the lower edges of the frame may be used for straightening up the sides of the form.

The bail or end frame member 2 is also U-shaped, and the end of its legs 6 are pivotally connected to the sides of the frame member 1. The bail 2 connects and also encloses the open end of the frame member 1, the upper flange 3 being cut away to allow the bail to be moved up and down, as shown in Figs. 5 and 6. In the sides of the frame member 1 is slidably mounted a bar 7, the end of the bar being provided with tongues 8 which engage in suitable slots 9 formed in the ends of said sides.

At the outer side, the upper edge of the bar 7 is bevelled off at 10 on a radius which is struck approximately from the center of the pivotal connection of the bail 2. The metal at the transverse portion of the bail 2 is also bent upwardly from the lower edge of the bail to form the resilient tongues 11. Pref-

erably the tongues 11 are provided with wedging surfaces 12 at the lower portions, for engaging with the bevelled surface 10 of the bar 7.

5 In using the device the frame is held over the type page, and the bar 7 is placed against one end of the page. The frame is then drawn back and lowered into position for enclosing the page. The sides of the frame fit closely 10 against the sides of the page, and the type are clamped by pressure between the ends of the frame. As the bail 2 is forced down into clamping position, the wedging surfaces 12 of the fingers 11 engage the bevelled surface 15 10 of the lock bar 7 and the bar is wedged inwardly to press the type against the resilient abutment 5, which is provided at the opposite end of the frame. When the bail 2 is in the horizontal position, the fingers 11 20 engage the outer surface of the bar 7 below the shoulder formed by the bevelled surface 10. The movable parts 7 and 2 are thereby locked securely in position, and the frame may be handled quite roughly without danger 25 of having the type drop out. The resilience in the pressure members 5 and 11, compensates for any slight differences which might occur in the length of the page and also for any changes which might occur after the 30 holder is clamped. By beveling the lower edges of the frame member 1, as shown in Figs. 3 and 4, the holder can be readily slipped over the page after a proof has been taken, and the page removed for corrections, which 35 can be readily made by raising the bail 2 to relieve the pressure on the type without removing the holder.

Having thus described my invention I claim:

- 40 1. In a type page holder, a rectangular frame, pivotal means for clamping the type form in the frame, and resilient means integral with said frame for holding the type under pressure after the form has been clamped.
- 45 2. In a type page holder, a rectangular frame, means pivoted to the frame for clamping the type form in the frame, and a yieldable plate in one end of the frame for maintaining pressure on the type.
- 50 3. In a type page holder, a rigid frame means pivoted to the frame for clamping the type form in the frame, and a resilient abutment in the frame against which the 55 clamping means operates.
- 55 4. In a type page holder, a rectangular frame, a resilient abutment in the frame, and pivotal means for compressing and holding the type form against the abutment.
- 60 5. In a type page holder, a frame having rigid sides fitting closely over the type form and having a pivotal end portion, and means integral with said frame for compressing the type form between the ends of the frame.
- 65 6. In a type page holder, a rectangular

frame for enclosing the type body, a bar extending across one end of the frame, said bar being slidably mounted in the frame, and pivotal means for forcibly moving and holding the bar inwardly.

7. In a type page holder, a U-shaped frame member extending completely around three sides of the type body, a bar extending across the open end of the frame member and slidably mounted therein, and a U-shaped end frame member having the ends of its legs pivotally connected to the sides of said frame member and having a wedging surface co-operating with said bar for clamping the type body against the closed end of said member.

8. A page frame comprising a rectangular frame consisting of two U-shaped, pivotally connected frame members, a bar extending across the open end of one of said frame members and slidably mounted therein, the other of said members having a wedging surface formed in its transverse portion co-operating with said bar for clamping the type form against the transverse portion of the other member.

9. A page frame comprising a U-shaped frame member for enclosing three sides of the type form, a bar extending across the open end of said frame member and slidably mounted therein, and a U-shaped member hinged to said member for wedging the bar inwardly.

10. In a page frame, a rectangular frame, a bail hinged to the sides of the frame, a bar extending across the frame and slidably mounted therein, the bar and the bail having cooperating surfaces whereby the bar is forced inwardly when the bail is forced down.

11. In a type page holder, a rectangular open ended frame, a bail hinged to the open end of the frame, and a bar extending across the frame, the bail having a resilient portion for wedging the bar inwardly to clamp the type form in the frame.

12. A page frame comprising a rectangular open ended frame, a bail hinged to the open end of the frame, a bar extending across the frame, the bail having a wedging surface for acting on the bar to force the same inwardly and the frame having a resilient abutment strip at the closed end thereof.

In witness whereof, I hereunto subscribe my name to this specification.

EDWARD B. HOWE.
